The ornamental design for a navigational device front panel, as shown and described.

DESCRIPTION

FIG. 1 is a perspective view of a navigational device front panel according to the present invention;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The rear elevation view is plain and conforms to the surfaces shown in the figures.
